UNITED STATES PATENT OFFICE.

WILLIAM C. CHESBRO, OF ST. JOSEPH, MISSOURI.

AUTOMATIC IMPRESSION TRIPPER FOR PRINTING PRESSES.

Application filed May 14, 1921. Serial No. 469,467.

To all whom it may concern:

Be it known that I, WILLIAM C. CHESBRO, a citizen of the United States, residing at St. Joseph, in the county of Buchanan and State of Missouri, have invented certain new and useful Improvements in Automatic Impression Trippers for Printing Presses, of which the following is a specification, reference being had therein to the accompanying drawing.

My invention relates to improvements in that class of impression trippers which are used for tripping and thereby removing the form a predetermined distance from the platen; for preventing the printing of a sheet of paper laid on said platen; and the objects of my improvements are, first; to provide a mechanism of this class, which shall be used as a detachable attachment, which can readily and easily be secured on presses now generally in use, by an inexperienced person, and which can be done without altering or in any way changing the press, second; to provide a simple, substantial and durable attachment of this class which shall automatically trip the impression of a form from any sheet of paper, cardboard and the like, while said sheet is not placed against the conventional feed gauges, thereby preventing the printing on said sheet from being out of proper position and also preventing the printing from being applied to any part of the tympan sheet, third; to provide manually operated electric circuit controlling means whereby the controlling circuit can be closed while distributing ink and can be opened when it is desired to print an impression on the upper one of said tympan sheets, for use in making ready as it is termed, fourth; to so construct the impression tripper, that it shall be cheap in cost of manufacture and can be packed in the minimum amount of space, for storage or shipment.

I attain these objects by the mechanism illustrated in the accompanying drawings, in which:

Figure 1 is a longitudinal section of the impression tripper and of a printing press cut on the dot and dash line 1 1, seen in Fig. 2, showing the parts of the tripper out of operative position. Fig. 2 is a rear view of the tripping parts of the mechanism, seen in Fig. 1, certain parts of the printing press being broken away. Fig. 3 is a side view of the tripping part of the mechanism

and of a press, looking toward the right side of the press, certain parts of which are broken away.

Fig. 4 is an enlarged section of the tripping mechanism, similar to Fig. 1, showing the parts of the tripper in position, with an impression tripped thereby. Fig. 5 is a top plan in detail of the tripping mechanism. Fig. 6 a top view of the automatically operated circuit closer in closed position. Fig. 7 is a view similar to Fig. 6, showing the parts of the automatic circuit closer in open position, a certain portion of the platen being broken away. Fig. 8 is a slightly enlarged top view of the platen and of the circuit closers carried thereby. Fig. 9 is an enlarged section in detail of a portion of one of the grippers and of the two gripper electrodes carried thereon, cut vertically on the line 2 2, seen in Fig. 8, looking toward the left.

Fig. 10 is an enlarged section in detail of one of the tympan electrodes, cut vertically on the line 3 3, seen in Fig. 8, looking toward the left. Figure 11 is an enlarged top view of one of the gripper electrodes showing its securing means in detail. Fig. 12 is a section in detail, of the parts seen in Fig. 11, cut vertically on the line 4 4, looking toward the rear. Fig. 13 is a side view, enlarged, of the automatically operated circuit closer, seen in Figs. 6 and 7.

My invention comprises the channel bar 5, which bar is secured by the U bolts 6 (see Fig. 5,) on the legs 7 of the bed 8 of the press, as seen in Fig. 1. The lower end portions of said legs are provided with the tie-bar 9, formed therewith.

The upper ends of the space legs 10 are secured on the lower surface of said channel bar. The lower ends of said space legs rest upon said tie-bar, for determining the height at which said channel bar is secured on the bed legs 7.

The plate 11 is secured on the upper surface of said channel bar. The iron bound electro-magnet 12 is secured on said plate. The helical exciting coil 13 is placed in said magnet. The armature 14 is secured on the central portion of the rod 15, which is mounted for slidable movement through said magnet 12. The gong hammer 16 is loosely mounted on the upper end of said rod. The gong 17 is secured on the upper end of the post 18, the lower end of which is secured in the plate 11.

The lower end of the rod 15 is passed loosely through an opening formed through the drive bar 19, which is oscillatably mounted on the channel bar 5. Said rod is provided with the pin 20, which is secured in its lower end and extends beyond the sides of said rod, for lifting the free end portion of said drive bar, which latter portion is adapted to gravitate from the position seen in Fig. 4, to the position seen in Fig. 1.

The engaging hook 21 is formed on the drive bar 19 and is lifted by said bar until its path of travel is in alinement with the lug 22, by the hereinbefore described electro-magnetic lifting means, after which movement toward the left, of the bed legs 7, (by the described connecting parts,) moves said hook into engagement with said lug.

Said lug 22 is secured on the gear carrier 23. The upper end of said gear carrier is oscillatably mounted on the shaft 24, the ends of which are oscillatably mounted in the frame sides 7" of the press. The internal gear segment 25 is secured on one side of the lower end portion of said gear carrier.

The pinion segment 26 is detachably secured on the shaft 27, by the triangularly formed key 26', one corner of which key is pressed into said shaft by tightening the cap 26".

The ends of said shaft 27 are oscillatably mounted in said frame sides.

The central portion of the throw-off pin circle 28 is secured on the shaft 27. The extremities of said pin circle are of hook shape, for contact alternately with the shaft 24, for limiting its oscillation and the therewith connected shaft 27.

The stud 29 is secured in the central portion of said pin circle 28 and extends therefrom into the indicated channel 30, which is formed in the adjacent face of the L shaped throw-off piece 31.

The lower end of the connecting rod 32 is oscillatably connected with unchanneled end of said throw-off piece. The upper end of said connecting rod is crank connected with the back shaft 33, the end portions of which are oscillatably mounted in the flanges 33' which are formed on the bed 8.

The journals 34 (of which one is shown in Fig. 3,) are formed on the extremities of said back shaft, eccentrically thereto. Said journals are rod and crank connected with the crank disks 35 by the connecting rods 36. Said disks are secured on the ends of the main shaft 37, which is rotatable in the frame sides 7".

Referring to Figs. 1 and 2, one side of the battery 38 is connected with the electric conductor 39 which leads thence around one of the channeled portions of the spool 40, which is loosely mounted on the bed shaft

7'. Said conductor extends from said spool to the binding post 41, which is connected with one end of the coil 13 by the conductor 42. The other side of said battery is connected with the adjacent frame side 70 7", by the conductor 43.

The other end of said helical coil is connected with the conductor 44 which leads therefrom to the binding post 45.

Conductor 46 leads from said binding post 75 around the other channeled portion of spool 40, extends therefrom around the spool 46', (see Fig. 1,) thence to its connection with the manually operated circuit closer 47.

Said circuit closer is connected by the conductor 48, with the fixed electrode 49, which is secured on the upper front corner portion of one of the frame sides 7", as seen in Fig. 13. The coating electrode 50 is secured on the hereinafter described rocker 85 of the press, which carries said electrode into contact with the electrode 49.

The conductor 51 connects the electrode 50 with the insulated metal strip 52, at 53". Said strip is secured on the under side of the strip of insulation 52'. Said metal strip is connected by the screw 53 with the tympan electrode 54, the rear end of which is secured on said insulation by the screw 53, which is secured in any desired one of the apertures 53', for adjusting the position of said tympan electrode.

The gripper electrodes 55 and 56 are slideable on the gripper 57, the rear end of which is laterally adjusted and secured on the gripper bar 58. The gripper electrode 59 is similarly mounted on the gripper 60, which latter is similarly secured on said gripper bar.

The bearing brackets 61 and 62 are secured respectively, on the rear corners of the platen 63. The gripper bar 58 is oscillatably mounted in the rear ends of said brackets.

The take-up screw 64 is screwed through a threaded aperture formed through the bracket 62 and against the adjacent end of the gripper bar journal, for taking up longitudinal movement of said gripper bar, thereby preventing lateral movement of grippers 57 and 60 and the thereon carried electrodes 55, 56 and 59. Said take-up screw is provided with the lock nut 65, for holding said screw in its adjusted position.

Each one of the three gripper electrodes is secured on its respective gripper, by an eccentrically mounted cam 66, which is oscillated against the metal strip 67 for pressing the latter against its respective gripper. Said cam is manually moved by its thumb lever 66'. Said electrodes are adjusted and thus secured in proper position to coordinate with the various proportions of sheets of paper to be printed.

The platen 63 is provided with the front and rear bails 68 for holding the tympan 120

sheets tightly and smoothly stretched on said platen, as hereinafter described.

The ends of the strip of insulation 52 are respectively secured on the intermediate 5 portions of the brackets 61 and 62.

Platen 63 is adjustably secured on the platen rocker 69, which latter is secured on the rocker shaft 70, the ends of which shaft are oscillatably mounted in the frame sides 10 7". Said rocker is oscillated by a cam and friction roll, which form no part of this invention, and are therefore neither shown nor described.

The locking arm 71 is formed with and 15 depends from the rocker 69. The lug 72 is formed on the free end of said arm. By the previously mentioned rocker oscillating means, said rocker is oscillated clockwise, until the lug 72 is thereby carried against 20 the frame projection 72', over the free end of the oscillatably mounted lock bar 73, after which the upper end of said lock bar is oscillated into position, beneath said lug, by the spring 74, for locking said rocker and 25 the therewith connected parts, against movement, while taking an impression. The free end of said lock bar is moved outward by the cam 75, (of which but a part is shown in Fig. 1,) the surface of which cam is rotated past the friction roll 76.

The gripper bar 58 with the thereon secured grippers 57 and 60, is yieldably held in the position seen in Fig. 1, by the spring 77, one end of which is secured to the gripper-bar arm 78 and the other end secured to the gripper cam 79, with the friction roll 80 thereby held against the face of said cam. The slot 81 is formed through the lower end portion of said cam, through 35 which the friction roll 82 extends, for guiding the lower end of said cam. Said friction roll 82 is rotatably mounted on the adjacent frame side 7". The upper end of 40 said cam is oscillatably connected with the 45 adjacent end of the platen 63.

In the tripping mechanism, the recover bar 86 is provided with the adjusting screw 87 which is screwed through a threaded aperture, formed through the bent free end 50 of said bar.

The other end of said recover bar is oscillatably connected with the gear carrier 23.

Said recover bar 86 is moved toward the right by the return movement of the bed 55 legs 7, for recovering the hereinbefore described movement of the tripping mechanism.

In the operation of my invention, a form of type or the like (not shown,) is secured 60 on the bed 8 of the press, a plurality of tympan sheets 83 are secured upon the platen 63, by the bails 68, after which the manually operated switch 47 is opened.

Power is then applied for rotating the 65 drive shaft 85, which by unshown gears

drives the press. The previously mentioned breaking of the formerly described electric circuit, renders the previously described impression tripper inoperative, and movement of the form makes an impression of it 70 upon the upper one of said tympan sheets, after which the power is removed from said drive shaft.

From this impression, the location of the feed gauges 84 (see Fig. 8,) are determined, 75 which gauges are placed in the manner well known to the pressmen's art.

Said pressman then makes incisions through the upper one of said tympan sheets, in which incisions the extremities of 80 the tympan electrode 54 are inserted, as seen in Fig. 10.

Said pressman then adjusts the grippers 57 and 60 for holding the sheet of paper to be printed, after which he so adjusts the 85 gripper electrodes that their lower edges 59' (see Fig. 12,) rest upon the tympan electrodes 54. He then releases said grippers and places a sheet of paper to be printed, upon the upper, printed one of the tympan 90 sheets 83, after which he closes the switch 47 and applies power to the drive shaft 85, for again operating the press.

Should either the rear or the left edge, or both of said edges of said sheet of paper 95 be not placed against said gauges, the thus exposed tympan electrode would be contacted by the corresponding gripper electrode, thereby closing therethrough the previously described electric circuit, upon which the 100 following described impression tripping actions take place.

Electric energy passes from the battery 38, (see Fig. 5,) through the conductor 39, the binding post 41, into the magnet coil 13, 105 (see Fig. 1,) thence through conductor 44, the binding post 45, the conductor 46, the manually operated switch 47, thence through the conductor 48, the electrodes 49 and 50, the conductor 51, (see Fig. 6,) the 110 insulated metal strip 52, (see Fig. 10,) thence through the screw 53, into the tympan electrode 54, thence through the gripper electrode 59, (see Fig. 8,) through the gripper 60, the gripper bar 58, the bearing 115 brackets 61 and 62, the platen 63, (see Fig. 1,) the platen rocker 69 and the rocker shaft 70, into and through the frame side 7" and thence through conductor 43 to the other side of the battery 38, thereby energizing the 120 magnet 12, seen in Fig. 1.

The thus energized magnet draws the armature 14 from the position seen in Fig. 1, to the position seen in Fig. 4, thereby suddenly lifting the therewith connected rod 15, 125 which similarly lifts the gong hammer 16. The inertia of said hammer lifts it against the gong 17, after which it gravitates to the position shown in Fig. 4, resting upon the upper end of said rod, thereby giving warn- 130

ing that the sheet to be printed is in an improper position.

Said rod lifts the pin 20 against the drive rod 19, thereby lifting the hook 21, until its hook stop 21' is against the lug 22, with the line of travel of said hook in alinement with said lug.

In the operation of the press, the movement toward the left of the legs 7, which 10 similarly move the channel bar 5, thereby moves the drive rod 19 from the position seen in Fig. 1, to the position seen in Fig. 4.

This moves the therewith connected gear carrier and the gear segment 25, thereby rotating the pinion segment 26 clockwise, thereby similarly rotating the shaft 27. This movement of said shaft, similarly oscillates the pin circle 28, which similarly moves the pin 29.

20 The engagement of said pin 29 with the channel 30, which is formed in the adjacent face of the throw-off piece 31, oscillates the latter counter-clockwise, thereby moving the connecting rod 32 upward, from the position seen in Fig. 1, to the position seen in Fig. 4. This movement oscillates the crank connected back shaft 33 clockwise, from the position seen in Fig. 3, to such position that the thereon eccentric journals 34 30 move said back shaft and the therewith connected bed 8 from the platen 63, thereby moving the before mentioned form such distance from said platen, that the thereon secured tympan sheets 83 and said misplaced 35 sheet of paper receive no impression from said form.

The press feeder at this juncture hears the previously described sound of the gong 17 after which he properly places said sheet of 40 paper against the gauges 84, seen in Fig. 8.

The bar 86 (see Fig. 1,) recovers the previously described movement of the gear carrier 23, which recover movement is actuated by return movement of the bed legs 7.

45 After this recover movement has taken place, further operation of the press prints said properly placed sheet of paper, during which operation the tripping mechanism is idle.

50 Having fully described my invention, what I claim as new, and desire to secure by Letters Patent, is:

1. In an impression tripper for printing presses; an electric circuit; energizing 55 means for electrically energizing said circuit; impression-tripper driving means; moving means whereby said driving means is moved into operative position for driving said impression tripper, said moving means 60 being actuated by said electric energy; a plurality of tympan electrodes in said circuit, said electrodes being adjustably secured over the platen and insulated from the latter; a like plurality of gripper electrodes 65 in said circuit, said gripper electrodes

being adjustably secured on the grippers of said press; and moving means formed of parts of said press whereby said electrodes are moved for bringing said gripper electrodes into contact with said tympan electrodes.

2. The combination with the back shaft of a printing press said shaft being provided with a crank secured thereon and with a journal formed eccentrically thereto on each one of its ends and oscillatably mounted bed legs by which said back shaft is carried; of oscillating means whereby said legs are oscillated; a connecting rod 70 the upper end of which is connected with said crank; a trip shaft; rod moving means loosely mounted on said trip shaft the upper end of said rod moving means being pivotally connected with the lower end of said connecting rod for moving the latter longitudinally; a pin circle secured on said trip shaft; a stud secured in the central portion of said pin circle, said stud being extended therefrom into engagement

75 with a channel formed in the adjacent face of said rod moving means; a pinion segment detachably secured on said trip shaft; an oscillatably mounted gear carrier; an internal gear segment secured on the free end portion of said gear carrier said gear segment being in engagement with said pinion segment; a lug secured on said gear carrier; mounting means secured on said bed legs; a drive bar one end portion of which is oscillatably mounted on said mounting means; a hook formed on the free end portion of said drive bar said hook being adapted to normally pass beneath said lug; electro-magnetic lifting means whereby the free end portion of said bar is lifted to such

80 position that the line of travel of the therewith formed hook is in alinement with said lug; moving means whereby said bar and the thereon formed hook are moved for moving the latter against said lug thereby moving

85 said gear carrier in one direction; gear-carrier returning means actuated by movement of said bed legs for returning the movement of said gear carrier; an energized

90 electric circuit for energizing said lifting means; and automatically operated circuit controlling means for controlling said electric circuit.

3. In an automatic impression tripping mechanism; a source of electric energy; a circuit for directing said electric energy; an electromagnet in said circuit; an armature for said magnet; a slidably mounted rod on which said armature is secured; a drive bar 100 for driving said tripping mechanism; and lifting means on the lower end of said rod whereby said bar is lifted into operative position for operating said tripping mechanism.

4. In a device of the class described, the

combination of a printing press including a supporting frame, a form support, a platen arrangement oscillatively mounted in said support frame, an adjustable gripper arrangement cooperating with said platen arrangement, electric circuit means, a trip mechanism for operation upon closing of the circuit to hold said platen arrangement and form out of impression taking relation, adjustable electrodes carried by the platen arrangement, adjustable electrodes carried by said gripper arrangement, said platen electrodes and gripper electrodes cooperating with sheets placed upon the platen to provide an automatic control means for operation in electric circuit.

5. In a device of the class described, the combination of a printing press including a supporting frame, a form support, a platen arrangement movably mounted in said supporting frame, an adjustable gripper arrangement in cooperation with said platen arrangement including a bar member pivotally mounted with respect to said platen, and gripper arms extending therefrom over the platen and being slidable laterally of the platen, electrode members adjustable longitudinally of said gripper arms, an insulated bar carried by said platen arrangement, a conductor bar carried below said insulated bar, electrode members carried by said insulated bar and conductor bar of the platen arrangement being laterally adjustable over the platen thereon, electric circuit means, a trip mechanism for operation upon closing of the circuit by means of said electrodes to hold said platen arrangement and form out of impression engaging relation, said platen electrodes and gripping arm electrodes cooperating with sheets placed upon the platen to provide an automatic control means for said electric circuit.

10. In a tripping mechanism for printing presses, the combination with a press including a stationary frame portion, a platen arrangement, legs pivotally supported by said stationary frame, a form, and a shaft eccentrically supported by said legs and having said form mounted thereon, of a shaft carried by said frame, an arm supported on the last mentioned shaft having a gear segment carried thereon adjacent the free end thereof, a second shaft supported by said frame, a pinion on said second shaft in meshing relation with the gear segment of said arm, lever means connecting said pinion shaft with the eccentrically mounted form carrying shaft, and means for operating said arm whereby said form may be tripped out of operating relation to said platen arrangement.

15. In a tripping mechanism for printing presses, the combination with a press including a stationary frame portion, a platen arrangement, legs pivotally supported by said frame, a form, and a shaft eccentrically supported by said legs and having said form mounted thereon, of a shaft carried by said frame, an arm supported on the last mentioned shaft having a gear segment carried thereon adjacent the free end thereof, a second shaft supported by said frame, a pinion on said second shaft in meshing relation with the gear segment of said arm, lever means connecting said pinion shaft with the eccentrically mounted form carrying shaft, and means for operating said arm whereby said form may be tripped out of operating relation to said platen arrangement.

7. In a tripping mechanism for printing presses, the combination with a press including a stationary frame portion, a platen arrangement, legs pivotally supported by said frame, a form, and a shaft eccentrically supported by said legs and having said form mounted thereon, of a shaft carried by said frame, an arm supported on the last mentioned shaft having a gear segment carried thereon adjacent the free end thereof, a second shaft supported by said frame, a pinion on said second shaft in meshing relation with the gear segment of said arm, lever means connecting said pinion shaft with the eccentrically mounted form carrying shaft to operate the latter for tripping said form upon movement of said segmental arm, an electric circuit embodying a circuit maker and breaker arrangement on said platen arrangement, an electromagnet carried by said legs in said electric circuit, an armature for said electromagnet, a drive bar pivotally carried by said legs adapted for movement upon movement of said electromagnet armature, said drive bar when the circuit is closed adapted to be moved into operating relation with the arm upon which said gear segment is mounted so that when the legs of said printing press move to an impression taking relation said drive bar will move said arm to trip the form out of operative relation with the platen arrangement, and a recovery bar pivotally carried by said arm adapted to engage a part of the pivotally mounted legs when the latter are moving away from said frame to right the position of the form.

8. In a tripping mechanism for printing presses, the combination with a press including a stationary frame portion, a platen arrangement, legs pivotally supported by said stationary frame, a form, and a shaft eccentrically supported by said legs and having said form mounted thereon, of a shaft carried by said frame, an arm supported on the last mentioned shaft having a gear segment carried thereon adjacent the free end thereof, a second shaft supported by said frame, a pinion on said second shaft in meshing relation with the gear segment of said arm, lever means connecting said pinion shaft with the eccentrically mounted form carrying shaft to operate the latter for tripping said form upon movement of said segmental arm, an electric circuit embodying a circuit maker and breaker arrangement on said platen arrangement, an electromagnet carried by said legs in said electric circuit, an armature for said electromagnet, a drive bar pivotally carried by said legs adapted for movement upon movement of said electromagnet armature, said drive bar when the circuit is closed adapted to be moved into operating relation with the arm upon which said gear segment is mounted so that when the legs of said printing press move to an impression taking relation said drive bar will move said arm to trip the form out of operative relation with the platen arrangement, and a recovery bar pivotally carried by said arm adapted to engage a part of the pivotally mounted legs when the latter are moving away from said frame to right the position of the form.

9. In a tripping mechanism for printing presses, the combination with a press including a stationary frame portion, a platen arrangement, legs pivotally supported by said stationary frame, a form, and a shaft eccentrically supported by said legs and having said form mounted thereon, of a shaft carried by said frame, an arm supported on the last mentioned shaft having a gear segment carried thereon adjacent the free end thereof, a second shaft supported by said frame, a pinion on said second shaft in meshing relation with the gear segment of said arm, lever means connecting said pinion shaft with the eccentrically mounted form carrying shaft to operate the latter for tripping said form upon movement of said segmental arm, an electric circuit embodying a circuit maker and breaker arrangement on said platen arrangement, an electromagnet carried by said legs in said electric circuit, an armature for said electromagnet, a drive bar pivotally carried by said legs adapted for movement upon movement of said electromagnet armature, said drive bar when the circuit is closed adapted to be moved into operating relation with the arm upon which said gear segment is mounted so that when the legs of said printing press move to an impression taking relation said drive bar will move said arm to trip the form out of operative relation with the platen arrangement, and a recovery bar pivotally carried by said arm adapted to engage a part of the pivotally mounted legs when the latter are moving away from said frame to right the position of the form.

10. In a tripping mechanism for printing presses, the combination with a press including a stationary frame portion, a platen arrangement, legs pivotally supported by said stationary frame, a form, and a shaft eccentrically supported by said legs and having said form mounted thereon, of a shaft carried by said frame, an arm supported on the last mentioned shaft having a gear segment carried thereon adjacent the free end thereof, a second shaft supported by said frame, a pinion on said second shaft in meshing relation with the gear segment of said arm, lever means connecting said pinion shaft with the eccentrically mounted form carrying shaft to operate the latter for tripping said form upon movement of said segmental arm, an electric circuit embodying a circuit maker and breaker arrangement on said platen arrangement, an electromagnet carried by said legs in said electric circuit, an armature for said electromagnet, a drive bar pivotally carried by said legs adapted for movement upon movement of said electromagnet armature, said drive bar when the circuit is closed adapted to be moved into operating relation with the arm upon which said gear segment is mounted so that when the legs of said printing press move to an impression taking relation said drive bar will move said arm to trip the form out of operative relation with the platen arrangement, and a recovery bar pivotally carried by said arm adapted to engage a part of the pivotally mounted legs when the latter are moving away from said frame to right the position of the form.

In testimony whereof I affix my signature.

WILLIAM C. CHESBRO.
